(57) **CLAIM**

The ornamental design for an automobile and/or toy replica thereof, as shown and described.

DESCRIPTION

FIG. 1 is a front elevational view of an automobile and/or toy replica thereof showing our new design;

FIG. 2 is a rear elevational view thereof;

FIG. 3 is a top plan view thereof;

FIG. 4 is a left side elevational view thereof;

FIG. 5 is a right side elevational view thereof;

FIG. 6 is a left, front perspective view thereof; and,

FIG. 7 is a right, rear perspective view thereof.

The hidden surfaces from the bottom, obscured by a rear bumper, the wheels, and inside the wheel wells, but visible in the figures form no part of the claimed design. The broken line showing on the automobile and/or toy replica thereof is for the purpose of illustrating environmental structure and forms no part of the claimed design.
